Attorney, Agent, or Firm—Thomas E. Tyson; Paul S. Drake

[73] Assignee: International Business Machines Corporation, Armonk, N.Y.

CLAIM

[**] Term: 14 Years

The ornamental design for the front panel for a data processing system, as shown.

[21] Appl. No.: 480,180

DESCRIPTION

[22] Filed: Feb. 13, 1990

FIG. 1 is a reduced top, front and right side perspective view of a front panel for a data processing system showing our new design;

[52] U.S. Cl. D14/115

FIG. 2 is a front elevational view thereof;

[58] Field of Search D14/100, 114, 115, 124,

FIG. 3 is a right side elevational view thereof;

D14/125, 239; D13/162, 184, 199;
360/97.01-99.12; 361/331, 332, 380, 381,
390-395, 415, 426

FIG. 4 is a bottom plan view thereof;

References Cited

FIG. 5 is a rear elevational view thereof wherein the broken lines are shown for illustrative purposes only and form no part of the claimed design;

U.S. PATENT DOCUMENTS

FIG. 6 is a left side elevational view thereof; and,

D. 249,343 9/1978 Ronzani D14/115
D. 285,795 9/1986 Chandler et al. D14/115

FIG. 7 is a top plan view thereof.
